UNITED STATES PATENT OFFICE.

EDWARD CHESHIRE, OF MILWAUKEE, WISCONSIN, ASSIGNOR TO MILLER SAW TRIMMER COMPANY OF MICHIGAN, OF ALMA, MICHIGAN, A CORPORATION OF MICHIGAN.

SHEET SEPARATING AND MOVING DEVICE.

1,145,403.

Specification of Letters Patent.

Patented July 6, 1915.

Original application filed July 22, 1909, Serial No. 508,896. Divided and this application filed November 9, 1909, Serial No. 527,004. Renewed May 29, 1915. Serial No. 31,312.

To all whom it may concern:

Be it known that I, EDWARD CHESHIRE, a citizen of the United States, residing at Milwaukee, in the county of Milwaukee and State of Wisconsin, have invented new and useful Improvements in Sheet Separating and Moving Devices, of which the following is a full, clear, concise, and exact description, reference being had to the accompanying drawing, forming a part of this specification.

My invention relates to automatic sheet separating and moving devices, and particularly to devices for separating the top sheet from the remainder of a pile and pushing it forward to be seized by an automatic feeding device.

The object of my invention is the provision of an improved device of the above character, and one which will be efficient, certain and regular in its operations.

The embodiment of my invention which will be described below has been described and illustrated in my copending application Serial No. 508,896, filed July 22, 1909, "Paper feeding and handling devices", of which this application is a division.

For an understanding of the invention, reference is to be had to the following description taken in connection with the accompanying drawings, which show a device illustrating the principal features of the invention, and in which—

Figure 1 is a side elevation of the device; Fig. 2 is a rear elevation; Fig. 3 is a plan; Fig. 4 is a view similar to a portion of Fig. 1, but with the parts in a different position; Fig. 5 is a partly sectional detached view drawn to an enlarged scale, illustrating the sheet lifting shoe and related parts in still another position; and Figs. 6 and 7 are an inverted plan and a perspective view respectively, illustrating the form and operation of the sheet-lifting shoe.

The invention is shown in the drawings as used in connection with an automatic feeder for platen presses, but this is only one of a number of possible applications and is used for purposes of illustration merely.

Referring now to the drawings; D² is a table for supporting the pile of paper. This table is slidably mounted in the feed

box by means of a pillar D³ which slides in a guide D⁴. An intermittent upward movement is imparted to the table D² at the removal of each sheet from the pile, the effect being that the top of the pile is maintained at a constant level. The mechanism by which the movement of the table D² is effected forms the subject matter of my co-pending application Serial No. 527,003, filed November 9, 1909.

In the device illustrated the feed box has detachably mounted thereon a hood F which carries the operating parts of the feeder. Slidably mounted in lugs G¹ (Figs. 2 and 3) extending inwardly from the sides of the hood F are a pair of pins G² which are carried by a presser bar G, compression springs G³ being inserted between the presser bar and the lugs G¹, which springs tend to hold the presser bar in its lowermost position, i. e. against the upper edges of the feed box. When the presser bar G is in its lowermost position and a pile of paper is in place upon the table D², the presser bar G presses upon the paper along the front edge thereof and forms a stop against which the pile of stock is intermittently moved, as described above. Cams G⁴, mounted on a rotating shaft F² are provided for intermittently raising the presser bar and allowing one of the sheets of paper upon the pile to be moved forward. These cams each have a projection thereon, which projections engage the rollers of cam levers G⁵ which are pivoted to the hood, and the ends of which engage in notches in the pins G². As the cams G⁴ revolve, therefore, the levers G⁵ are operated to raise the presser bar and allow the paper to be moved outward beneath it.

The sheet separating mechanism proper H is actuated by means of a bell crank lever H¹ rockably supported in the hood F adjacent the center of the front end thereof. Movement is imparted to the bell crank lever H¹ by means of a cam H² secured to the shaft F². The cam H² is formed with a small starting hump H³ and the configuration of the remainder of the cam is such that a slight forward movement is imparted to the bell crank lever by the hump H³, and, after the bell crank lever has remained stationary for a short time, a considerable further for-

ward movement is effected. The bell crank levers then remains stationary for a period and is afterward allowed by the cam to return to its original position, such return being effected by a spring H⁴. The slight preliminary movement caused by the hump H³ causes the sheet lifting shoe to operate.

Suitably secured to the hood is a bracket H²⁴ to which is pivoted at H²⁵ a horizontal rod H⁵ carrying on its outer end a block H⁶ which carries the sheet lifting device. The rod H⁵ is provided with a lug H²⁶, having therein a segmental slot H²⁷, through which passes a pin H²⁸, carried by the bracket, which pin serves to limit the movement of the rod H⁵ about its pivot H²⁵. The block H⁶ is adjustably mounted upon the rod H⁵ so that to provide for the use of various sizes of sheets of paper and carries a bent end stop H⁷, the block H⁶ being adjusted upon the rod H⁵ so that the end stop H⁷ presses lightly against the rear of the pile of paper. Pivoted to the upper part of the block H⁶ is a link H⁸ having pivoted to the outer end thereof the pneumatic lifting shoe H⁹. The link H⁸ is provided with a projection H¹⁰ arranged to be engaged and moved by a block H¹¹ secured to a movable rod H¹² which derives its movement from the bell crank lever H¹, to which it is connected through the intermediary of an arm I, as will hereinafter be described. Rockably supported in the block H⁶ is a spindle H¹³ carrying at each end a lever to which is secured a paper separating dog H¹⁴. The spindle H¹³ is formed with a projection H¹⁵ thereon which engages in a recess H¹⁶ formed in the lower side of the block H¹¹ so that the latter, in its forward and backward movements, will intermittently rock the spindle H¹³ to raise and lower the dogs H¹⁴. The lifting shoe H⁹ is provided with a rear plate H¹⁷ the ends of which extend slightly downward (Fig. 7) and behind which the dogs H¹⁴ engage when they are raised. As the block H¹¹ is moved forward by reason of the bell crank lever H¹ being moved by the hump H³ of the cam H² and the rod H¹² being consequently pulled forward, it engages the projection H¹⁰ and thus raises the lifting shoe H⁹ to lift a sheet of paper. The pivot of the lifting shoe being located near the rear edge thereof, this edge will rise first so that the paper will be lifted from its rear edge, which is desirable. Just as the shoe H⁹ takes its uppermost position, it strikes rods H⁵ and H¹², and is thereby again brought into parallelism with the top of the pile of sheets. Practically at the same time as the shoe H⁹ is raised the rear face of the recess H¹⁶ engages against the projection H¹⁵ of the spindle H¹³ and effects a downward rocking movement thereof to lower the dogs H¹⁴, the result being that these dogs slip downwardly and forwardly

from the rear plate H¹⁷ and enter beneath the lifting shoe before the sheet of paper lifted thereby has had time to fall, and engages the top of the second sheet to hold it against movement. In order that the dogs H¹⁴ may press firmly down upon the pile of paper, they are provided with stop projections H²⁹, which engage the levers H¹³ and render the dogs H¹⁴ rigid with these levers during the downward movement thereof. Fig. 5 shows the position of these parts just before the lifting shoe H⁹ rises. Fig. 4 illustrates the position of the dogs as they are being forced downward by the block H¹¹, the dogs being shown as just entering beneath the shoe H⁹ to catch a sheet of paper.

In order that the shoe H⁹ may be enabled to perform the above described lifting operation its lower face is formed with a plurality of concentric connected circular grooves H¹⁸ (Fig. 6) and with a central hole H¹⁹ communicating by means of a hose H²⁰ with a pump H²¹ actuated by a cam on the counter shaft F². Just as the shoe H⁹ is being lifted, the pump is actuated by its cam to create a suction in the hole H¹⁹ and concentric grooves H¹⁸, so that, as the shoe is raised, a sheet of paper will be pneumatically gripped thereby and raised with it. Immediately after the sheet has been raised the movement of the pump is reversed and consequently the sheet falls. Before, however, the sheet has had time to reach the pile again the dogs H¹⁴ have entered beneath the lifting shoe and the sheet of paper consequently falls with its rear edge resting upon the points of these dogs whereby it is separated from the remainder of the pile. The dogs H¹⁴ press upon the pile of stock sufficiently hard to prevent the removal of any other sheets of paper when the separated sheet is withdrawn, the pressure being maintained by the flat face of the member H¹¹ at the rear of the notch H¹⁶.

In order to prevent the lifting foot H⁹ from raising two sheets at once owing to the paper being drawn into the concentric grooves H¹⁸ and thereby creating a suction upon the second sheet of paper in the pile, I form a slight depression H²² (Figs. 6 and 7) between the rear edge of the lifting shoe and the circular grooves H¹⁸. The effect of this is clearly shown in Fig. 7. When the top sheet is sucked against the shoe it adapts itself to the configuration of the lower surface thereof and therefore creates a small passage between itself and the next sheet, whereby air is admitted between the two sheets and the chance of more than one being raised by the lifting shoe is minimized.

All of the above described operations occur during the slight movement of the rod H¹² due to the hump H³ effecting the pre-

liminary movement of the bell crank lever H^1 .

While the above operations have been going on the sheet pushing device has begun its movement. The sheet pushing device is constructed as follows: An arm I is attached to the free end of the bell crank lever H^1 by means of a friction joint and carries at its end a cross bar I^1 to which are attached 5 friction disks I^5 arranged to engage the top sheet of paper and move it forward. It is to this arm I that the rod H^{12} is pivotally connected, as at H^{23} (Fig. 4). When the bell crank lever is in its upper and rearmost 10 position, *i. e.*, just before it is operated by the hump H^3 of the cam, the cross bar I^1 is situated somewhat above and slightly to the rear of a spacing pin I^2 mounted upon the rod H^5 , the lifting shoe H^6 being then in the 15 position shown in Fig. 5. When the hump H^3 begins to press upon the roller of the bell crank lever H^1 the lever I is moved downward until the cross bar I^1 presses upon the top of the spacing pin I^2 and remains in that position until the cam H^2 begins to move the bell crank lever H^1 again. 20 When this occurs, the lever I will be forced to rock about its frictional pivot until the cross bar I^1 slips off the spacing pin I^2 and moves downward to engage, by means of 25 the friction disks I^5 , the top sheet of paper and move it forward into the position shown in Figs. 1 and 3 to be seized by the feed grippers or the like, it being remembered 30 that before the cross bar I^1 moves from above the spacing pin, the lifting shoe and dogs will have separated a sheet in the manner described above. The spacing pin I^2 exactly determines the time at which the 35 friction disks will strike the paper and the distance forward through which it will be moved, regardless of buckling of the paper, should any occur.

When the above operations have taken 40 place, and a sheet of paper has been moved forward and removed by suitable grippers or the like, according to the type of machine with which the device is being used, and when the cam H^2 has rotated far 45 enough, the bell crank lever H^1 will be returned to its original position by means of the spring H^4 , and the lifting shoe and related parts will resume the position shown in Fig. 5. During the first part of the 50 return movement of the bell crank lever H^1 , the cross bar I will be raised, and the friction disks I^5 will be lifted from the paper, the stiffness of the friction connection between the arm I and the bell crank lever 55 being sufficient to effect this. After the cross bar I has been raised to a predetermined extent, further lifting is prevented by the engagement of a pin I^3 , with which the arm I is provided, with the under side of the rod H^{12} . The pin I^3 will then slide against the

rod H^{12} during the remainder of the return movement of the bell crank lever, the arm I at the same time rocking about its frictional connection. By this means, a uniform distance between the cross bar and the 70 top of the spacing pin I^2 at the beginning of the operation is insured.

Just before the above operations take place the projections of the cams G^4 will have operated the cam levers G^3 to raise the 75 pins G^2 and therefore the presser bar G to enable the sheet to be pushed out in front.

Having thus described my invention, what I claim as new and desire to secure by Letters Patent, is:

1. Mechanism for separating the top sheet from a pile of sheets and moving it toward a feeding device, comprising means for separating the top sheet from the remainder of the pile, means for subsequently engaging 80 the separated sheet and moving it forward, and a spacing device for engaging said sheet moving means at the first part of its movement, thereby to prevent said sheet moving means from engaging the top sheet until the 85 latter has been released by the separating device.

2. Mechanism for displacing the top sheet from a pile of sheets, comprising a pivoted member, means for intermittently rocking 90 said member toward and away from the pile, a sheet engaging and moving device pivoted to said member, and a spacer disposed so as to be engaged by said device during the first part of the movement of the latter, thereby 95 to prevent said device from engaging the sheet prematurely.

3. In mechanism for separating the top sheet from a pile of sheets, a pneumatic sheet lifting shoe having a plurality of suction 105 spaces in its lower surface and having a depression extending rearwardly from said suction spaces, and means for operating said shoe, said operating means and said shoe being so arranged that the shoe extends inwardly from the edge of the pile of sheets 110 for the purposes set forth.

4. Mechanism for separating the top sheet from a pile of sheets, comprising a pneumatic sheet lifting shoe having a suction 115 orifice therein and formed with a plurality of grooves connecting with said suction orifice and with a depression extending rearwardly from said grooves, and said shoe being disposed so as to extend inwardly from the rear edge of the pile of sheets, for the purposes set forth.

5. Mechanism for separating the top sheet from a pile of sheets, comprising a pneumatic sheet lifting shoe arranged adjacent 125 to the rear edge of the pile of sheets, means for moving said shoe down to engage the top sheet and upward to lift the same, and a loosely mounted separating member arranged to bear against said shoe when the 130

latter is in its lower position and to enter beneath the shoe when the latter is raised, for the purposes set forth.

6. Mechanism for separating the top sheet from a pile of sheets, comprising a pneumatic sheet lifting shoe arranged adjacent to the rear edge of the pile of sheets, means for moving said shoe down to engage the top sheet and upward to lift the same, a loosely mounted separating member arranged to bear against said shoe when the latter is in its lower position and to enter beneath the shoe when the latter is raised, means for moving said separating member down to engage the top of the pile, and a stop arranged to be engaged by said separating member when the latter has come into engagement with the top of the pile.

7. Mechanism for separating the top sheet from a pile of sheets, comprising a pneumatic sheet lifting shoe, arranged adjacent to the rear edge of the pile of sheets, means for moving said shoe downward to engage the top sheet and upward to lift the same, said shoe being provided with guide ways on its rear face, and a loosely mounted separating member arranged to bear against said guide ways when the shoe is in its lower position, and to enter beneath the shoe when the latter is raised.

8. Mechanism for separating the top sheet from a pile of sheets, comprising a support, a substantially horizontal arm pivoted to said support, means for rocking said arm about its pivot, and a pneumatic sheet lifting shoe pivoted to said arm toward the rear edge of said shoe, so that upon said arm being rocked to lift said shoe, the rear edge of the latter will be lifted first.

9. Mechanism for separating the top sheet from a pile of sheets, comprising a support, a substantially horizontal arm pivoted to said support, means for rocking said arm about its pivot, a pneumatic sheet lifting

shoe pivoted to said arm toward the rear edge of said shoe, so that upon the arm being rocked to lift said shoe, the rear edge of the latter will be lifted first, and means for engaging said lifting shoe when in its uppermost position to bring it into parallelism with the top of the pile of sheets.

10. Mechanism for separating the top sheet from a pile of sheets, comprising a support, an arm pivoted to said support, a pneumatic sheet lifting shoe pivoted to said arm, means for imparting a rocking movement to said arm to raise and lower said shoe, a lever pivoted to said support, means for imparting a rocking movement to said lever in an opposite direction to the movement of said arm, a dog pivoted to said lever, and means for limiting the movement of said dog relatively to said lever, said dog and said lever being so disposed that said dog bears upon the top of the pile of sheets when said lever is in one of its positions, and engages behind the said pneumatic shoe when said lever is in its other position.

11. Mechanism for separating the top sheet from a pile of sheets and moving it toward a feeding device, comprising a pneumatic sheet lifting device, a sheet moving device, arranged to operate after the top sheet has been lifted by said lifting device, means for engaging the top of the pile beneath the lifted sheet and clamping the same against movements, and means, controlled by said sheet moving device, for locking said clamping means in its operative position during the movement of a sheet by said sheet moving means.

In witness whereof, I have hereunto subscribed my name in the presence of two witnesses.

EDWARD CHESHIRE.
